UNITED STATES PATENT OFFICE.

MENDEL SHENK, OF BROOKLYN, NEW YORK.

VENTILATING WINDOW-SASH LOCK.

1,082,773.

Specification of Letters Patent. Patented Dec. 30, 1913.

Application filed September 21, 1912. Serial No. 721,591.

To all whom it may concern:

Be it known that I, MENDEL SHENK, a subject of the Czar of Russia, residing at 1711 Lincoln Place, Brooklyn, county of 5 Kings, and State of New York, have invented certain new and useful Improvements in Ventilating Window-Sash Locks, fully described and represented in the following specification and the accompanying 10 drawings, forming a part of the same.

The present invention is adapted for use with windows having upper and lower sliding sashes, and it relates to a means for locking the upper sash when lowered a sufficient distance while the lower sash is 15 raised about the same distance, to permit a certain amount of ventilation.

The means provided in the present invention consists of a locking-arm hinged to the 20 upper sash so that it may project across the top of the lower sash in contact therewith when the upper sash, or both sashes are arranged for ventilation.

When hinged to the upper sash it may 25 be turned to clear the lower sash so that both sashes may be moved freely, but when set in its operative position it is locked by suitable means to the inner edge of the window-casing, thus holding the upper sash 30 from any movement. The locking means is preferably secured about five inches above the top of the bottom sash when the latter is closed, to permit the raising of the bottom sash, if desired, sufficiently for ventilation. 35 This locking-arm connecting the upper sash with the window-casing, holds the upper sash from moving and prevents the lower sash from rising above a certain height, thus allowing the upper sash, or 40 both upper and lower sashes, to be open with safety for continuous ventilation of the apartment.

The invention will be understood by reference to the annexed drawing, in which—

45 Figure 1 is an elevation, and Fig. 2 a plan of the fixtures with the parts of the window connected thereto; Fig. 3 is a perspective view showing the locking-arm hinged to the upper sash as in Figs. 1 and 50 2; and Fig. 4 shows a modified construction of the locking-arm of Fig. 3.

a designates the inner frame of the window-casing, and *b* the outer frames.

c designates the parting-strip set in the

frame *a*, and *d* a stop-bead upon the frame *b* 55 at the inner side of the casing.

e designates the stile of the upper sash, and *e'* its bottom rail.

f designates the stile of the lower sash, and *f'* its top rail. 60

The locking-arm is shown affixed to the stile *e* a few inches above its bottom rail *e'* and formed as a wire link having a cross-bar *g* at one end for a hinge-pin, with side-bars *g'* projected therefrom and the free 65 end of the arm having a loop *g''*. This locking-arm is hinged to the stile *e* by a hinge-plate *h* having a transverse groove *i* to receive the hinge-pin *g* and secured to the stile *e* by screws *j*. With this construction the arm may be turned transversely and its free end lie against the stop-bead *d*, as indicated by the dotted lines *g''* in Fig. 2. The upper sash may be lowered with the arm in this position until the free end of 75 the arm enters the notch *m* of the locking device, which may have the form of the bracket *l* secured to the stop-bead *d* or inner margin of the window-frame. When thus adjusted, the free end of the arm may 80 be locked in the notch by any suitable means, as the bolt *k*, threaded in the bracket *l*, to extend into the notch and engage the open loop *g''* of the arm, as shown in Fig. 3. Such relation of the screw to the link is indicated by the dotted circle *k'* indicating the 85 position of the screw within the open loop in Fig. 1.

It is immaterial how the locking-arm is mounted upon or hinged to the stile *e* provided it can swing over the top of the lower sash to engage the bracket and be secured by the locking-bolt. For greater security, the locking-bolt *k* may be formed so as to be opened only by means of a key, and it may be 90 so shaped or fixed upon the bracket that it could not be rotated by a tongs extended through either of the ventilating openings. Such locking of the locking-arm to the window-frame holds the upper sash from 100 moving and the contact of the arm with the top of the lower sash prevents the same from being lifted above the desired height, and both sashes are thus locked from further movement when the upper one is lowered, 10 and the lower one is lifted, sufficiently for ventilation. The arm may be hinged to the stile *e* at any distance, as ten inches,

above the bottom of the upper sash to secure the ventilation desired; but not near enough to the edge of either sash to permit the locking-screw being reached by any one through the ventilating opening.

The locking-arm is hinged to swing clear of the top of the lower sash when it is desired to move either of the sashes freely, and the arm is shown in Figs. 1 and 2 parallel with the plane of the upper sash so that it may lie in a line with the parting-strip *e* to clear the lower sash when either sash is moved. The locking-arm may, if desired, be made as shown in Fig. 4, where a piece of wire is bent at the middle of its length to form an open slot *g*, and its terminals bent at right angles to the axis of the arm and fitted to opposite grooves in the hinge-plate *h*. This construction is equivalent in all respects to that shown in Figs. 1, 2 and 3. The fixtures are readily attached to the window-sashes and frames by a few screws, and then serve effectually to prevent the sashes from being opened beyond the desired limit when they are arranged for ventilation.

The locking-device is set for operation by swinging the arm transverse to the lower sash, then lowering the upper sash and securing the locking-arm in its operative position. The lower sash can then be raised into contact with the locking-arm, but no higher.

It will be observed that the locking-arm is, by its hinge-plate, held movably while it is connected permanently with the part upon which it is jointed, and while it is secured to such part it is always in readiness for use, and not liable to be misplaced or lost, as with a removable fixture. It will also be observed that the locking-arm extends from the inner face of the stile *e* to the nearest surface on the window-casing, which is a broad flat surface of the stop-bead *d*. The hinge-plate supports the hinge of the locking-arm upon the surface of the stile so that the stile requires no cutting or recessing for applying the fixture.

The locking-arm, by its relation to the stile and the stop-bead, is formed of a single straight and strong piece which requires no joints or links and can be swung parallel with the upper sash so as not only to clear the lower sash when unlocked, but permitting both the sashes to be moved freely without the necessity of detaching the locking-bolt from the sash, as in some previous constructions.

The permanent connection of the locking-arm in its working position, and its form and capacity to swing parallel between the sashes, furnishes a cheap and simple con-

struction for which I have made a special claim. The form of the locking-arm and bracket is immaterial. The means for locking the arm in the position described permits the lower sash to be raised at the same time that the upper sash is lowered, thus affording a double amount of fresh air, which is a much more healthful arrangement than where only the upper sash is lowered. The locking-arm may be formed in any manner to be engaged by the screw-bolt *k*.

Having thus set forth the nature of the invention, what is claimed herein is:

1. In a ventilating sash locking device, the combination, with a window casing having upper and lower sashes, of the hinge-plate *h* attached to the stile of the upper sash and having a transverse groove *i*, the one-piece locking-arm having an integral hinge-pin *g* at one end fitted to the socket of the hinge-plate and adapted to clear the hinge-plate when turned against the upper sash and to swing across the top of the lower sash against the stop-bead, and the stop-bead having the bracket *l* with the notch *n* to receive the end of the locking-arm, and means to lock the said arm in the said notch.

2. In a ventilating sash locking device, the combination, with a window-casing having upper and lower sashes, of the hinge-plate *h* having a transverse groove *i*, a locking-arm having side-bars *g*, a hinge-pin *g* connecting one end of the side-bars and fitted to the said groove, the opening between the side-bars being adapted to clear the hinge-plate when the arm is in a line with it, and the bracket *l* upon the adjacent edge of the window-casing adapted to receive the locking-arm, and having the bolt *k* threaded in the bracket to lock the end of the arm thereto.

3. In a ventilating sash locking device, the combination, with a window-casing having upper and lower sashes, of the hinge-plates *h* secured upon the stile of the upper sash, a locking-arm having one end hinged in the said hinge-plate and adapted to swing from a position parallel with the upper sash across the top of the lower sash, and a bracket upon the window-frame having a bolt adapted to engage the end of the locking-arm to lock the same to the bracket.

In testimony whereof I have hereunto set my hand in the presence of two subscribing witnesses.

MENDEL SHENK.
